UNDERWOOD COMPUTING MACHINE COMPANY, OF NEW YORK, N. Y., A CORPO-
RATION OF NEW YORK.

TYPE-WRITING MACHINE.

1,262,604.

Specification of Letters Patent. Patented Apr. 9, 1918.

Application filed November 28, 1913. Serial No. 803,454.

To all whom it may concern:

Be it known that I, FRED WALSLEBEN, a citizen of the United States, residing in the borough of Queens, city of New York, in the 5 county of Queens and State of New York, have invented certain new and useful Improvements in Type-Writing Machines, of which the following is a specification.

This invention relates to line-spacing, 10 mechanisms of typewriting machines, and is especially valuable in connection with machines in which the usual letter-feeding carriages are returned to initial positions by means of power-driven devices.

15 One of the principal objects of the invention is to provide a simple and efficient construction for this purpose.

The source of power is connected directly to the carriage itself instead of to the line-spacing mechanism as heretofore; so that 20 instead of initially giving the line-spacing mechanism a quick throw, the source of power first returns the carriage, and at the final portion of the return movement there- 25 of, the line-spacing is effected, utilizing largely the momentum of the carriage. Thus the necessity is avoided of imparting 30 to the platen a sharp or quick line-spacing movement, which is liable to effect a relative displacement between the platen and the work-sheet or sheets thereon. A part on the carriage engages a part on the machine frame, so that the movement of the carriage 35 itself causes the line-spacing mechanism to operate.

The opposition offered by the line-spacing mechanism to the movement of the carriage, lessens the shock due to the momentum of 40 the carriage, and the carriage is brought gradually to rest. The speed of the return- 45 ing carriage, which is not very great, does not impart an excessively rapid movement to the platen, and hence there is no liability of the platen creeping ahead of the work- sheets, or of the work-sheets creeping ahead 50 of the platen in line-space direction.

Moreover, since the line-spacing is accomplished by the movement of the carriage, it becomes practical for the operator to re- 55 turn the carriage by a handle on the right-hand side thereof, the handle being placed directly upon the carriage. All the operator needs to do is to take hold of said handle and run the carriage back as far as it will

go, the line-spacing operation being automatically performed. The operator, therefore, has the option of returning the carriage either by the use of the right-hand handle, or by the use of the carriage-returning handle which is usually placed at the 60 left-hand end of the carriage, and which is usually also a part of the line-spacing mechanism. Some operators are apt to give the line-spacing handle too jerky a movement, thus not only tending to effect relative displacement between the platen and the work-sheet thereon, but also tending to injure the mechanism; but by means of the present improvements this difficulty is avoided, since the operator can return the carriage by 70 means of a separate handle usually provided at the right-hand end of the carriage, and at the conclusion of the return stroke of the carriage the line-spacing mechanism will be slowly operated.

In order to accommodate short runs of the carriage, where it is desired to leave a broad blank margin on the left-hand border of the work-sheet, the device which operates the line-spacing mechanism is carried by the adjustable margin gage, which is usually provided for regulating the extent of the return stroke of the carriage. As this gage is adjusted for various lengths of written lines, the line-space actuator is adjusted with it, so that the line-spacing operation takes place at the proper time in the proper manner at the conclusion of each return stroke of the carriage, whether such stroke be a short one or a long one.

Another advantage gained by the present improvements is that the difficulty is avoided which has heretofore been experienced, of connecting up a power-driven device to the line-spacing mechanism of a typewriter, 95 such connections usually being numerous and complicated and liable to get out of order and apt to be unsatisfactory in use.

Other features and advantages will hereinafter appear.

In the accompanying drawings,

Figure 1 is a sectional front elevation of the left-hand portion of the front of the carriage, showing details of the mechanism which actuates the line-spacer during the return of the carriage; the normal position of the line-spacing device being shown in dotted lines, and the position of the same

at the end of the line-spacing operation being shown in full lines.

Fig. 2 is a perspective of a margin gage having fixed thereon a rack which is adjustable with the margin gage and is brought into use at the conclusion of the return stroke of the carriage to effect the line-spacing of the platen.

Fig. 3 is a part sectional perspective view 10 of a part of the frame of an Underwood front-strike typewriting machine, and the carriage, platen, and platen frame thereof, showing the parts in normal positions.

Figure 4 is a sectional elevation taken 15 through the margin gage, the pinion, and racks which operate the line-spacing mechanism.

Fig. 5 is a front elevation of a modified line-space actuating mechanism.

20 The usual platen 1 is journaled by axle 2 in frame 3, on a carriage 4. The types make successive impressions, until a line is written, the carriage feeding step by step under the control of a rack 4^a thereon and 25 an escapement pinion 4^b. The carriage 4 is then returned to the right (to start a new line of writing) by suitable power-driven means, which may be a power pinion 5 to engage rack 6, fixed on the rear of the carriage. The pinion itself may be controlled 30 in any well-known manner, to start and stop rotating.

To effect the line-spacing of the platen 1, a pinion 7, pivoted on the carriage 4, is 35 forced when drawn along by the latter, to rotate, by reason of its engagement with a stationary rack 8, and thereby the pinion is caused to draw back or to the right a second rack 9, connected to line-space lever 10. 40 The latter has an arm 11 to force back a plunger 12, which carries a pawl 13 into engagement with one of the teeth 14 on line-space wheel 15, and thereby rotate the platen 1.

45 The rack 9, which is drawn back or to the right by the pinion 7 to line-space the platen, works in a track or groove 16, which is protected by a plate 17. The forward or left-hand end of said rack is formed 50 with a neck 18, passing beneath the line-space lever 10, and having an ear or lug 19 to engage and rock the said lever. This forms a free-way or lost-motion space to the right of the line-space lever 10, whereby the 55 latter may be operated manually without disturbing the racks or pinion.

The stationary rack 8 is fixed upon the usual right-hand margin gage 20 and, is adjustable therewith along the front rails 21 60 and 25. The gage 20 carries a margin stop 26 in the path of a stop 27 on the carriage, the stop 26 forming an obstruction to arrest the carriage 4 at different positions corresponding to the adjustment of the margin 65 gage 20. This margin gage may be locked

in place by a dog 22, releasable by a finger-piece 23, and adapted to enter teeth 24 along the rail 25.

In Fig. 5 is shown a modified form in which a rack 8^a corresponding to the rack 8 70 is carried by the carriage, and is normally in mesh with the pinion 7. The butt end of the rack 8^a, however, projects in advance of the carriage stop 27 (Fig. 3) a considerable distance, so as to strike the margin 75 stop 26 on the margin gage 20 before the carriage stop 27 strikes the same. This will cause the rack 8^a to remain stationary, thereby rotating the pinion 7 which travels relatively thereto, to draw the rack 8^a in the 80 direction of the arrow (Fig. 5), and thus actuate the line-space lever 10. The rack 8^a is also protected by the cover plate 17 and is provided with a guide slot 28 to engage 85 a stud 29.

The line-spacing mechanism also serves as a buffer to relieve the shock when the carriage strikes the stop at the conclusion of the return stroke. Moreover, it insures a smooth, even and relatively slow rotation 90 of the platen, and hence a proper advancement of the work-sheet. The spring 30 returns the plunger 12 and pawl 13, and hence also the line-space lever 10. The latter in turn, draws the rack 9 forward, or to the 95 left, as the pinion 7 runs along the rack 8 or 8^a toward the left-hand end thereof, when the carriage 4 again moves in letter-feeding direction.

The operator may return the carriage by 100 means of a handle 31 provided upon the right-hand end of the carriage, the line-spacing being effected automatically at the concluding portion of the carriage stroke, and the movement of the line-spacing mechanism being so slow as not to jar or disarrange the paper relatively to the platen. If he wishes to line-space without returning the carriage, he can do so by means of the handle 10.

110 Variations may be resorted to within the scope of the invention, and portions of the improvements may be used without others.

Having thus described my invention, I claim:

1. The combination with a carriage, of a line-spacing device upon said carriage including a rack which extends in the direction of the run of the carriage, a pinion upon said carriage meshing with said rack, and a 12 rack upon the machine frame to engage said pinion at the final portion of the run of the carriage from returning to begin a new line of writing.

2. The combination with a carriage, of a 13 line-spacing device upon said carriage including a rack which extends in the direction of the run of the carriage, a pinion upon said carriage meshing with said rack, a rack upon the machine frame to engage 14

5 said pinion at the final portion of the run of the carriage from returning to begin a new line of writing, and a margin gage adjustable to determine the width of the margin on the left-hand border of the work-sheet, the last-mentioned rack connected to the margin gage to be adjusted therewith.

3. The combination of a carriage, means connected directly to said carriage to return 10 the same, a line-spacing mechanism, means actuated by the return movement of the carriage as it approaches the end of said movement for operating said line-spacing mechanism, a margin gage for said carriage, 15 means connected to said margin gage to be adjusted therewith for coöperating with said line-spacing device as the carriage completes its return movement, said margin gage device including a rack and said carriage having a pinion in mesh with said rack, and a connection between said pinion and said line-spacing device.

4. The combination of a carriage, means connected directly to said carriage to return 20 the same, a line-spacing mechanism, means actuated by the return movement of the carriage as it approaches the end of said movement for operating said line-spacing mechanism, a margin gage for said carriage, 25 means connected to said margin gage to be adjusted therewith for coöperating with said line-spacing device as the carriage completes its return movement, said margin gage device including a rack and said carriage having a pinion in mesh with said rack, and a connection between said pinion and said line-spacing device, said line-spacing device including a lever which is manually operable independently of said margin 30 gage rack or device.

5. In a typewriting machine, the combination of a carriage, means for returning the same to the starting point of the writing line, a platen carried on said carriage, mechanism for line-spacing said platen, a rack 45 connected to said line-spacing mechanism, a stationary rack, and a pinion pivoted on said carriage to draw back the said rack and actuate the line-space mechanism when 50 said pinion moves over said stationary rack.

6. In a typewriting machine, the combination of a carriage, means for returning the same to the starting point of the writing line, a platen carried on said carriage, mechanism for line-spacing said platen, a rack 55 connected to said line-spacing mechanism, a stationary rack, and a pinion pivoted on said carriage to draw back the first-mentioned rack and actuate the line-space mechanism when said pinion moves over said stationary rack, the latter being positioned to engage the pinion and cause the operation of the line-spacing mechanism as the carriage nears the starting point of the writing 60 line.

7. In a typewriter, the combination of a carriage, means for returning it to the starting point of the writing line, a platen carried on said carriage, means for line-spacing said platen, a rack connected to said line-spacing means, a stationary rack, a pinion pivoted on said carriage to draw back said first-mentioned rack to actuate the line-space mechanism when said pinion passes over the stationary rack, and means for adjustably 70 locating the position of the stationary rack.

8. In a typewriter, the combination of a carriage, means for returning it to the starting point of the writing line, a platen carried on said carriage, mechanism for line-spacing said platen, a rack connected to said line-space mechanism, a margin stop, a rack on said margin stop, and a pinion pivoted on said carriage to draw back said rack and actuate the line-space mechanism when said 75 pinion passes over said rack on said margin stop.

9. The combination with a carriage, of a platen rotatably mounted on said carriage, line-space mechanism for said platen, and 80 a driving train for operating said line-space mechanism, said driving train including a rack and pinion traveling with said carriage and a rack stationary relative to said carriage, said stationary rack acting to effect a 85 driving action of said line-space mechanism by coming into mesh with said pinion and causing the latter to drive said traveling rack.

10. The combination with a traveling carriage, of a platen rotatably mounted on said carriage, a line-space mechanism for rotating said platen, a pair of oppositely facing racks, a pinion interposed between them and controlling their relative traveling movement, one of said racks being arranged to actuate said line-space mechanism when a relative traveling movement exists between the racks, and means controlled by the travel 100 of the carriage to effect said relative traveling movement.

11. The combination with a traveling carriage, of a platen rotatably mounted on said carriage, a line-space mechanism for said platen, a pair of oppositely facing racks, a 105 pinion interposed between them, one of said racks being arranged to actuate said line-space mechanism when a relative traveling movement exists between the racks, said racks being normally inactive but brought 110 into activity when the carriage reaches an intermediate position during its travel, and a margin gage adjustable to determine a limit of travel of said carriage, and also to determine the instant at which the racks 115 are brought into operation to effect a line-space movement of said platen.

12. The combination with a carriage, of a line-spacing device upon said carriage, including a rack which extends in the direc- 120 125 130

tion of the carriage travel, a pinion upon the carriage meshing with said rack, and means to engage said pinion at the final portion of the return movement of the carriage and 5 cause the pinion to be rotated on its axis by the movement of the carriage during said final portion of its return movement to thereby actuate the line-spacing device.

13. The combination with a carriage, of a 10 line-spacing device upon said carriage, including a rack which extends in the direction of the carriage travel, a pinion upon the carriage meshing with said rack, means to engage said pinion at the final portion 15 of the return movement of the carriage and cause the pinion to be rotated on its axis by the movement of the carriage during said final portion of its return movement, to thereby actuate the line-spacing device, and 20 a margin gage adjustable to determine the position at which the carriage is stopped at the completion of its return travel, said means adjustable with the gage, whereby the line-spacing device is operated when the carriage is at a position corresponding to the 25 adjustment of said gage.

14. In a typewriting machine, the combination of a carriage; a platen thereon; line-spacing mechanism, including an operating 30 lever; and a device for actuating said lever called into play automatically by the carriage, after the return movement of the latter has commenced, said device comprising a pair of spaced, parallel racks, one of which 35 is connected to said lever, and a pinion mounted on said carriage to travel therewith and interposed between said racks, so as to mesh with both racks and thereby effect an endwise movement of the first-named rack, 40 the other rack remaining stationary during a portion of the return movement of said carriage, so as to effect the rotation of said pinion at such time.

15. In a typewriting machine, the combination of a carriage; a platen thereon; line- 45

spacing mechanism, including an operating lever; and a device for actuating said lever called into play automatically by the carriage, after the return movement of the latter has commenced, said device comprising a 50 pinion mounted on said carriage to travel therewith, and a pair of spaced, parallel racks disposed on opposite sides of said pinion, one of said racks being constantly in mesh with said pinion to be shifted end- 55 wise thereby, and being connected to said lever to pull the same with it when so shifted, the other rack engageable with said pinion after a portion of the return movement of the carriage has been completed and 60 remaining stationary in such engagement throughout the remainder of said carriage movement, so as to effect the rotation of said pinion at such time.

16. In a typewriting machine, the combination of a carriage; a platen thereon; line-spacing mechanism, including an operating lever; and a device for actuating said lever called into play automatically by the carriage, after the return movement of the latter has commenced, said device comprising a pair of spaced, parallel racks, one of which has a lug to engage said lever, and a pinion mounted on said carriage to travel therewith, and interposed between said 70 racks, so as to mesh with both racks, and thereby effect an endwise movement of the first-named rack, the other rack remaining stationary during a portion of the return movement of said carriage, so as to effect the 75 rotation of said pinion at such time; the lug on said first-named rack being spaced from the body thereof, to permit said lever to be operated independently of said actuating device.

FRED WALSLEBEN.
